UNITED STATES PATENT OFFICE

95,632

DESIGN FOR A PLATE OR SIMILAR ARTICLE

Yukio Buma, New York, N. Y., assignor to
Morimura Bros. Inc., New York, N. Y., a cor-
poration of Japan

Application September 1, 1934, Serial No. 53,158

Term of patent 7 years

To all whom it may concern:

Be it known that I, Yukio Buma, a subject of
the Emperor of Japan, and a resident of the city,
county, and State of New York, have invented a
new, original, and ornamental Design for a Plate
or Similar Article, of which the following is a
specification, reference being had to the accom-
panying drawing forming part hereof.

The drawing is a plan view of a plate showing

my new design, a repeat unit of which is con-
tained between the dotted lines. Said unit is re-
peated about the circumference of the plate in
the relation indicated by the extension of the
detailed showing beyond the dotted lines.

I claim:

The ornamental design for a plate or similar
article, as shown and described.

YUKIO BUMA.
